(57) **CLAIM**

The ornamental design for a charger for an electronic vaping device, as shown and described.

DESCRIPTION

FIG. 1 is a rear perspective view of the charger for an electronic vaping device;

FIG. 2 is a rear view of the charger for an electronic vaping device;

FIG. 3 is a front view of the charger for an electronic vaping device;

FIG. 4 is a left side view of the charger for an electronic vaping device;

FIG. 5 is a right side view of the charger for an electronic vaping device;

FIG. 6 is a top view of the charger for an electronic vaping device;

FIG. 7 is a bottom view of the charger for an electronic vaping device; and,

FIG. 8 is a front perspective view of the charger for an electronic vaping device.

(Continued)

The broken lines in the figures represent portions of the article which form no part of the claimed design.

1 Claim, 5 Drawing Sheets
